UNITED STATES PATENT OFFICE.

JOHN C. EUBANK, OF CAMPBELLSVILLE, KENTUCKY.

SCYTHE-COUPING.

1,316,289.

Specification of Letters Patent. Patented Sept. 16, 1919.

Application filed August 21, 1918. Serial No. 250,791.

To all whom it may concern:

Be it known that I, JOHN C. EUBANK, a citizen of the United States, residing at Campbellsville, in the county of Taylor and State of Kentucky, have invented certain new and useful Improvements in Scythe-Couplings; and I do hereby declare the following to be a full, clear, and exact description of the invention, such as will enable others skilled in the art to which it appertains to make and use the same.

This invention relates to scythes and more particularly to means for attaching the scythe blade to the snathe.

The primary object of the invention is to provide a clamping sleeve which can be quickly and readily clamped into position to rigidly maintain the scythe blade shank in fixed relation with the snathe.

A further object of the invention is to provide a split clamping sleeve, the circumferential wall of which is extended outwardly to provide a longitudinally tapered channel for the reception of the blade shank when the latter is placed in operative position upon the flattened side of the snathe.

A still further object of the invention is to provide one end of the extended channel portion of the sleeve with a head whereby in the event that the sleeve should become casually loosened, it may be driven up on the taper of the blade shank.

A still further object of the invention is to provide the inner surface of the sleeve with a longitudinally disposed row of ratchet teeth which will permit of the sleeve being driven up tight on the heel shank and yet prevent its working back or becoming loose.

With these and other objects in view, as will appear as the description proceeds, the invention comprises various novel features of construction, combination and arrangement of parts, as will be fully described hereinafter and afterward claimed.

Referring to the drawings:

Figure 1 represents the bottom plan of the connection of the scythe blade with the snathe.

Fig. 2 represents a transverse sectional view taken on a plane indicated by the line 2-2 on Fig. 1, and

Fig. 3 represents a perspective view of the clamping sleeve.

In order that the construction and opera-

tion of the invention may be readily comprehended by those skilled in the art to which the invention relates, I have illustrated an improved embodiment thereof in the accompanying drawings and will now proceed to fully describe the same, in connection with said drawings, in which 1 is the snathe having a flattened under side 2 on which the tapered shank 3 of the scythe blade 4 is adapted to rest. The end of the shank 3 is provided with an offset lug 5 to lockingly engage within a recess or aperture 6 in the flattened side 2 of the snathe.

In order to rigidly connect the shank to the flattened side of the snathe, I employ my new and novel construction of clamping sleeve 7 as shown in Fig. 3. This sleeve is split longitudinally and provided with spaced laterally extending flanges 8 which are adapted to be drawn together by a clamping bolt 9 positioned therethrough.

The circumferential wall of the clamping sleeve is extended outwardly as at 10 to provide a tapering channel 11 extending from one end of the sleeve to the other adapted to receive the tapered shank 3. The smaller end of the outwardly extended portion 10 is provided with a head 12 by which the sleeve may be driven on the taper of the shank, if for some reason the sleeve should casually work loose after it has once been adjusted into position.

The inner surface of the sleeve is provided with a longitudinally extending row of teeth 13 which are preferably of ratchet formation so as to permit of the clamping sleeve being readily driven up on the taper of the shank, and which will bite into the snathe and prevent the sleeve from casually working loose or off the taper of the shank 3. It will be noted that the sleeve 7 is split at one side between the offset portion 10 which engages the shank 3 and the teeth 13, so that when the bolt 9 is tightened, this will force the portion 10 and teeth 13 toward one another to clamp the shank against the snathe and to cause the teeth to bite the snathe.

From the foregoing it will be apparent that I have provided a simple and inexpensive clamping sleeve which can be quickly and readily adjusted into position to rigidly connect the blade shank to the snathe. While I have described and illustrated the preferred form of my invention, I desire to have it understood that such

changes in construction and arrangement of parts may be made when desired as are within the scope of the appended claim.

Having thus described my invention what 5 I claim as new is—

A scythe coupling embodying a clamping sleeve adapted to be slipped over the end of a snathe and to be contracted thereon, said sleeve having a longitudinal outwardly off- 10 set portion extending from one end to the other, and tapered from its outward to its inner end to snugly receive the tapered shank of a scythe blade, said sleeve being provided on the interior thereof diametri- 15 cally opposite said offset portion with in-

wardly extending teeth to bite the snathe opposite to the shank of the blade and prevent longitudinal movement of said sleeve, the sleeve being split at one side between said offset portion and teeth to permit the 20 sleeve to be contracted around the shank and snathe the sleeve having outstanding flanges at the split portion to be moved toward one another to contract the sleeve, and means extending through said flanges 25 to move them toward one another.

In testimony whereof I have signed my name to this specification.

JOHN C. EUBANK.
